Primary Examiner — Justin M Jonaitis*Assistant Examiner* — Jennifer S. Yosinski(74) Attorney, Agent, or Firm — Tommy S F Wang;
Wang IP Law Group, P.C.(57) CLAIM

The ornamental design for a garment rack as shown and described.

DESCRIPTION

FIG. 1 is a perspective view of a garment rack showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof with laundry bags coupled thereto.

The broken lines in FIGS. 1-8 are for the purpose of illustrating portions of the garment rack that form no part of the claimed design. The broken lines of the laundry bags in FIG. 8 illustrate unclaimed environment and forms no part of the claimed design.
